UNITED STATES PATENT OFFICE

2,309,459

ABDOMINAL SUPPORTER

Joseph J. Kispert, Jackson, Mich., assignor to
Kellogg Corset Company, Jackson, Mich.

Application August 22, 1940, Serial No. 353,698

14 Claims. (Cl. 2-27)

This invention relates to improvements in abdominal supporter.

The main objects of my invention are:

First, to provide an improved foundation garment, health belt or corset having provisions for most effectively supporting the abdomen of the wearer.

Second, to provide a foundation garment of the side lacing type fully covering and supporting the front and sides of the figure of the wearer so as to effectively sustain the abdomen without the presence of unsightly bulges.

Third, to provide a garment of the type described completely covering and supporting the abdomen and thighs of the wearer, the said garment being devoid of gaps or openings likely to result in unsightly bulges visible through the outer garments of the wearer and being effective at all times and in all positions of the wearer in sustaining and flattening the diaphragm of the wearer without discomfort, chafing and the like.

Fourth, to provide a foundation garment as described above having novel means for covering the pelvic arch so as to completely control and support the entire hip.

Further objects relating to details and economies of my invention will appear from the description to follow. The invention is defined in the claims.

A structure embodying the features of my invention is illustrated in the accompanying drawings, wherein:

Fig. 1 is a view in front elevation of a foundation garment in accordance with my invention, the belt portion of the garment being shown in partly open position to indicate the details of structure and arrangement thereof.

Fig. 2 is a fragmentary side view of the garment illustrated in Fig. 1, showing the side cluster lacing arrangement whereby the front and rear sections of the garment are drawn together and indicating the manner in which certain further elastic provisions for augmenting the supporting function of the garment are externally concealed, a portion of the cluster lacing arrangement being shown in closed or operative position and another portion in open or released position.

Fig. 3 is a fragmentary view generally similar to Fig. 2, illustrating the parts in released, inoperative position whereby details of construction and relation of the same may be understood, the coaction of the elastic connector for the front and side sections and the draw-up lacings being clearly indicated.

Fig. 4 is an enlarged fragmentary view illus-

trating in detail the lacing provisions for drawing the parts of the garment in operative position.

Fig. 5 is a fragmentary view in elevation illustrating the inner front side of a health belt constructed in accordance with a modified embodiment of my invention.

Fig. 6 is a fragmentary view in external side elevation further illustrating the details of the embodiment of Fig. 5.

Fig. 7 is an enlarged fragmentary view still further illustrating the construction of Figs. 5 and 6.

Fig. 8 is an elevational view illustrating a garment in accordance with a still further modified embodiment of my invention.

Fig. 9 is an enlarged fragmentary view in section on line 9-9 of Fig. 8.

One serious objection to most present-day foundation garments resides in the inadequacy of their provisions for supporting the abdomen of the wearer, which results from the fact that the body and closing members are drawn to operative position and held in that position by means acting concentratedly thereon at but a single location on the garment, or at a few widely distributed

points, so that the weight of the abdomen is not uniformly sustained or imposes excessive pressure on the holding means, with localized application of force and discomfort due to chafing and the like. Likewise, in such garments, it has generally been the case that gaps or openings are present or that the thighs of the wearer are inadequately covered, causing unsightly bulges.

Attempts have been made to eliminate this in one manner or another, but in the main have been ineffective so far as I am aware. The present garment affords a very effective, widely and uniformly distributed supporting of the abdomen, regardless of the wearer's position, a continuous coverage of the thighs and abdomen in the interests of comfort, and the production of a flat "Princess" line, unmarred by bulges.

In Figs. 1 to 4, inclusive, I illustrate a desirable adaptation of the invention in a health belt, generally designated by the reference numeral 1. The belt comprises a rear portion or section 3, side sections 4 continuously connected or stitched thereto, and composite auxiliary side and front sections 5. All the various sections are provided with stays in conventional manner, as indicated by the reference numeral 6. Elastic inserts 7 may be provided, also in accordance with conventional practice. The free forward edges of sections 5 have coacting hook and eye means 8 for initially securing the garment about the wearer's body. It will be appreciated that other means, for example,

a "Zipper," may be used in lieu of the hook and eye means illustrated.

The composite sections 5 are fabricated of the outer panels 9, on the forward edges of which the hook and eye means 8 are disposed, and the internally disposed flaps 10 stitched along vertical lines to the panels 9 adjacent the forward edges thereof. Adjacent the rear edge of each of the internal flaps 10 a row of eyelets 11 is disposed. The side sections 4 extend around the body of the wearer interiorly of the panels 9 and are each provided with a row of eyelets 12 at their forward extremities which lie adjacent and in opposed relation to the row of eyelets 11. The side and auxiliary sections 4, 5 respectively are connected together by a closed elastic connector lacing 13 threaded through the eyelets 11 and 12, as clearly illustrated in Fig. 1, to thereby resiliently hold the said sections in connected relation while yieldably supporting the abdomen of the wearer. Each row of eyelets has flexible stays 14 disposed on either side thereof and stitched or otherwise suitably secured to the respective side and auxiliary front sections.

Panels 9 of the auxiliary sections 5 extend externally of and in concealing relation to the elastic connector, rearwardly overlapping side sections 4 a substantial amount, and the said panels, adjacent the rear thereof, are each provided with a row of eyelets 15 (see Figs. 1 and 2). This row has stays stitched or otherwise suitably secured on either side thereof similar to stays 14. Adjacent the meeting point of the respective side sections 4 and rear section 3, and to the rear of the rear edge of panels 9, I provide a further similarly stayed row of eyelets 16 (see Fig. 2) on a forwardly extending flap 17 stitched to said sections. The rows of eyelets 15, 16 are in adjacent opposed relation.

Referring to Fig. 4, it will be noted that the side sections 4 have fixedly attached to the forward edges thereof a pair of flexible tapes 18, one in a position approximately over the abdomen of the wearer and the other in position over the diaphragm. These tapes are rove through adjacent eyelets 11 in the flap 10 on auxiliary section 5, then rearwardly internally of the garment through eyelets 16 and attached to flexible belt or strap sections 19 having buckles 20 attached thereto. The belts are also secured to the ends of two sets of cluster lacing 21 rove through the opposed eyelets 15, 16. Buckles 20 coact with further belts 22 stitched to the external panels 9 at an intermediate point thereon, whereby the tapes 18 and cluster laces may be drawn up upon tightening of the belts. Thus, the elastic connectors 13 are supplemented by tapes 18 in their action of drawing the rear flap 10 and side sections together at the forward edges of the latter, and this occurs simultaneously with the action of the cluster lacing in bringing the panels 9 into supporting relation to the abdomen of the wearer. The weight of the abdomen is very uniformly distributed and sustained by a plurality of supports and at a number of points or zones.

I contemplate that belts 22 will be provided of such extreme length that the ends thereof may be cut down by the wearer to the proper length for the wearer. Each of the auxiliary section panels 9 is provided with a pocket 23 into which the shortened end of the belt may be introduced so as to conceal the same and prevent the formation of a bump or bulge. The cluster lacing 21 extends for a substantial distance vertically on either side of the garment and serves to draw the

front of the garment uniformly into continuous supporting relation to the abdomen. As stated, the respective abdomen and diaphragm tapes are drawn up concurrently with tensioning of the 5 cluster lacing against the support at these points, and the elastic connection 13 between the auxiliary flap 9 and side section keeps this support a yielding one so that no discomfort will be experienced by the wearer.

10 It will be appreciated from the foregoing description that the auxiliary side and front sections 5 serve effectively as shields externally covering a goodly portion of the lacing provisions, namely, the rows of eyelets 11, 12 and closed 15 elastic lacing associated therewith, whereby this structure, notwithstanding its highly beneficial functioning, does not contribute an ugly, bulky appearance and provides a desirably smooth foundation for outer garments.

20 Referring to Figs. 1 and 2, the reference numeral 24 designates a web or band of elastic material of approximately five inches vertical width stitched at one side to the extreme forward edge of one of the side sections 4 and adapted to be 25 secured to a flap 25 stitched on the extreme forward edge of the other side section, hook and eye provisions 26 being preferably utilized for this purpose. The material of band 24 is preferably elastic in both directions, and it serves to completely cover the pelvic arch. All belts now on the market terminate a substantial distance above this point, but with band of two-way stretch material the stays of the corset may be regulated in length in accordance with the physical stretch of 30 the wearer, thereby enabling comfort to be had in sitting or all positions, while still giving complete control of the hips, thighs, and abdomen. It will be noted in Fig. 1 that the foundation garment illustrated affords complete coverage of the 35 wearer's body at all these points, so that bulges are eliminated. All the internal lacing is covered completely without using special shielding provisions, since, as stated, the auxiliary side and front section 5 has this function in addition to 40 augmenting and distributing the supporting action of the garment in the manner described.

In Figs. 5, 6, and 7, I illustrate a slightly modified embodiment of the foregoing invention, wherein the inner flap of the auxiliary side and front member, which member is here designated by the reference numeral 27, is drawn toward the side member 28 of the garment by the closed elastic lacing 29, the auxiliary section 27 rearwardly and externally overlapping section 28, as 50 described in connection with said preceding embodiment. The relatively wide ribbon-like tapes 30, one above the abdomen and the other above the diaphragm, are secured to side section 29 and laced through eyelets of the auxiliary and rear section and secured to belt takeup means 31 55 in the manner described above. This structure is characterized by all the advantages described in connection with the embodiment of Figs. 1 to 4, inclusive. Fig. 5 clearly illustrates the arrangement and advantages of the pelvic band 24 described in connection with those figures.

In Figs. 8 and 9, I illustrate a still further adaptation of the invention. In this form, the auxiliary and side sections 32, 33 respectively are 60 held in position and manually adjusted by pairs of elastic tapes 34 rove through the eyelets in the forward edge of the side section 33 and the rearwardly extending flap 35 of the auxiliary section. These tapes extend rearwardly and are secured to the buckle 16 by which the cluster 75

lacing 37, generally similar to that of the foregoing embodiments, is tensioned. Pockets 38 in the auxiliary section receive the ends of the belt 39 to conceal the same and avoid projections, in the manner described in connection with Figs. 1 to 4.

The embodiment of Figs. 8 and 9 also includes novel structure for associating hose supporting members on the garment, in the form of looped flexible elastic tapes or bands 40 having an adjusting element 41, one end of the tapes being secured to the bottom of the external panel of the auxiliary section panel 32 and the other end to the bottom forward corner of the side section 33.

In all the foregoing embodiments, the weight of the abdomen is divided and distributed to a plurality of supports each disposed in the most effective manner to sustain its share. The result is increased comfort for the wearer, with no possibility of chafing or irritation due to unduly localized action. The elastic connector employed is relieved of the duty of supporting the entire abdominal weight, but functions effectively as a yielding sustaining member whereby substantial support is afforded for the abdomen at all times whether standing, sitting, or changing from one of these positions to the other.

I have illustrated and described my improvements in embodiments which are very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. A foundation garment comprising connected rear and side body enclosing sections, there being a pair of said side sections extending forwardly of the rear section into encircling relation to the wearer's body, auxiliary sections coacting with said side sections, comprising panels extending to meeting relation at the front of the garment and flaps stitched to said panels adjacent the forward edge thereof and disposed internally of the panels, said panels having coacting securing means at said meeting edges and extending rearwardly in external overlapping relation to said side sections, coacting opposed rows of eyelets on the rear edge of said flaps and on said side sections adjacent the front thereof, closed elastic connectors interlaced with said rows to elastically maintain said auxiliary and side sections together adjacent the front of the latter, further coacting opposed rows of eyelets on the rear of said panels and adjacent the rear of said side sections, sets of cluster lacing rove through said further rows to draw the rear edge of said auxiliary sections rearwardly of said side sections, belt and buckle means secured to said cluster lacings and to said panels for tensioning the lacings, said panels having pockets to receive the belt of said last named means to conceal the same, and pairs of vertically spaced tapes disposed over the abdomen and over the diaphragm, said tapes being stitched to the forward edge of said side sections, rove through eyelets in the row in said flap, thence rearwardly through eyelets in the further row on said side sections, and secured to said belt and buckle tensioning means, whereby the action of said elastic connectors is augmented simultaneously with the tensioning of said cluster

lacing, said panels externally covering and concealing said connectors and preventing gaps in the garment whereby bumps and bulging are eliminated when the garment is worn.

5 2. A foundation garment comprising connected rear and side body enclosing sections, there being a pair of said side sections extending forwardly of the rear section into encircling relation to the wearer's body, auxiliary sections coacting with said side sections, comprising panels extending to meeting relation at the front of the garment and flaps stitched to said panels adjacent the forward edge thereof and disposed internally of the panels, said panels having coacting securing means at said meeting edges and extending rearwardly in external overlapping relation to said side sections, coacting opposed rows of eyelets on said flaps and on said side sections adjacent the front thereof, closed elastic connectors interlaced with said rows to elastically maintain said auxiliary and side sections together adjacent the front of the latter, further coacting opposed rows of eyelets on the rear of said panels and adjacent the rear of said side sections, sets of cluster lacing rove through said further rows to draw the rear edge of said auxiliary sections rearwardly of said side sections, means secured to said cluster lacings and to said panels for tensioning the lacings, and pairs of vertically spaced tapes disposed over the abdomen and over the diaphragm, coacting with said first named rows of eyelets, and secured to said tensioning means, whereby the action of said elastic connectors is augmented simultaneously with the tensioning of said cluster lacing, said panels externally covering and concealing said connectors and preventing gaps in the garment whereby bumps and bulging are eliminated when the garment is worn.

40 3. A foundation garment comprising connected rear and side body enclosing sections, there being a pair of said side sections extending forwardly of the rear section into encircling relation to the wearer's body, auxiliary sections coacting with said side sections, comprising panels extending to meeting relation at the front of the garment, said panels having coacting securing means at said meeting edges and extending rearwardly in external overlapping relation to said side sections, coacting opposed rows of eyelets on said panels and on said side sections adjacent the front thereof, elastic means interlaced with said rows to elastically maintain said auxiliary and side sections together adjacent the front of the latter, further coacting opposed rows of eyelets on the rear of said panels and adjacent the rear of said side sections, sets of cluster lacing rove through said further rows to draw the rear edge of said auxiliary sections rearwardly of said side sections, means secured to said cluster lacings and to said panels for tensioning the lacings, and pairs of vertically spaced tapes disposed over the abdomen and over the diaphragm, coacting with said first named rows of eyelets, and secured to said tensioning means, whereby the action of said elastic means is augmented simultaneously with the tensioning of said cluster lacing, said panels externally covering and concealing said elastic means and preventing gaps in the garment whereby bumps and bulging are eliminated when the garment is worn.

45 4. A foundation garment comprising connected rear and side body enclosing sections, there being a pair of said side sections extending forwardly of the rear section into encircling relation to

the wearer's body, auxiliary sections coacting with said side sections, comprising panels extending to meeting relation at the front of the garment, said panels having coacting securing means at said meeting edges and extending rearwardly in external overlapping relation to said side sections, elastic means to elastically maintain said auxiliary and side sections together adjacent the front of the latter, coacting opposed rows of eyelets on the rear of said panels and adjacent the rear of said side sections, sets of cluster lacing rove through said rows to draw the rear edge of said auxiliary sections rearwardly of said side sections, means secured to said cluster lacings and to said panels for tensioning the lacings, and pairs of vertically spaced tapes connected to said panels and side sections and secured to said tensioning means, whereby the action of said elastic means is augmented simultaneously with the tensioning of said cluster lacing, said panels externally covering and concealing said elastic means and preventing gaps in the garment whereby bumps and bulging are eliminated when the garment is worn.

5. A foundation garment comprising connected rear and side body enclosing sections, there being a pair of said side sections extending forwardly of the rear section into encircling relation to the wearer's body, auxiliary sections coacting with each of said side sections comprising panels extending to meeting relation at the front of the garment and adapted to be secured together in that relation, said panels extending rearwardly in external overlapping relation to said side sections, coacting opposed rows of eyelets adjacent the front of said panels and on said side sections adjacent the front thereof, closed elastic connectors interlaced with said rows to elastically maintain said auxiliary and side sections together adjacent the front of the latter, further coacting opposed rows of eyelets on the rear of said panels and adjacent the rear of said side sections, lacing rove through said further rows to draw the rear edge of said auxiliary sections up to said side sections, means secured to said lacing and to said panels for tensioning the lacing, and tapes stitched to the forward edge of said side sections, rove through eyelets in the front row in said panel, thence rearwardly through eyelets in said further row on said side sections, and secured to said tensioning means, whereby the action of said elastic connectors is augmented simultaneously with the tensioning of said lacing, said panels externally covering and concealing said connectors and preventing gaps in the garment whereby bumps and bulging are eliminated when the garment is worn.

6. A foundation garment comprising connected rear and side body enclosing sections, there being a pair of said side sections extending forwardly of the rear section into encircling relation to the wearer's body, auxiliary sections coacting with each of said side sections comprising panels extending to meeting relation at the front of the garment and adapted to be secured together in that relation, said panels extending rearwardly in external overlapping relation to said side sections, coacting opposed rows of eyelets adjacent the front of said panels and on said side sections adjacent the front thereof, closed elastic connectors interlaced with said rows to elastically maintain said auxiliary and side sections together adjacent the front of the latter, further coacting opposed rows of eyelets on the rear of said panels and adjacent the rear of said side

sections, lacing rove through said further rows to draw the rear edge of said auxiliary sections up to said side sections, and means secured to said lacing and to said panels for tensioning the lacing, said panels externally covering and concealing said connectors and preventing gaps in the garment whereby bumps and bulging are eliminated when the garment is worn.

7. A foundation garment comprising connected rear and side body enclosing sections, there being a pair of said side sections extending forwardly of the rear section into encircling relation to the wearer's body, auxiliary sections coacting with each of said side sections comprising panels extending to meeting relation at the front of the garment and adapted to be secured together in that relation, said panels extending rearwardly in external overlapping relation to said side sections, coacting opposed rows of eyelets adjacent the front of said panels and on said side sections adjacent the front thereof, elastic connectors interlaced with said rows to elastically maintain said auxiliary and side sections together adjacent the front of the latter, further coacting opposed rows of eyelets on the rear of said panels and adjacent the rear of said side sections, lacing rove through said further rows to draw the rear edge of said auxiliary sections up to said side sections, and means secured to said lacing and to said panels for tensioning the lacing, said connectors being secured to said tensioning means for actuation simultaneously with said lacing, said panels externally covering and concealing said connectors and preventing gaps in the garment whereby bumps and bulging are eliminated when the garment is worn.

8. A foundation garment comprising connected rear and side sections partially enclosing the body of the wearer, panels disposed at the ends of but separate from said side sections and extending to meeting relation to one another and adapted to be secured to one another at the free edges thereof, said panels each including a body covering panel substantially overlapping the ends of the first named section on which it is disposed externally of the same whereby gaps are eliminated, elastic means associated with the forward edges of said side sections and said panels to draw the former toward the free edges of the latter, cluster lacing interconnecting the rear edges of said panels and said side sections at a point spaced substantially rearwardly of the forward edge of the latter, tape means disposed over the abdomen and over the diaphragm and adjustably connecting the panels and side sections adjacent the elastic means to supplement the action thereof, belt tensioning means connected to said panels and to said cluster lacing and tape means for simultaneously actuating the same, said panels having pockets to receive and conceal the ends of said belt tensioning means, and elastic webbing of substantial width connected to one of said side sections and adapted to be connected to the other, said webbing covering the pelvic arch of the wearer and completing the coverage and support afforded by said garment.

9. A foundation garment comprising connected rear and side sections partially enclosing the body of the wearer, panels disposed at the ends of but separate from said side sections and extending to meeting relation to one another and adapted to be secured to one another at the free edges thereof, said panels each including a body covering panel substantially overlapping the ends of the first named section on which it

is disposed externally of the same whereby gaps are eliminated, elastic means associated with the forward edges of said side sections and said panels to draw the former toward the free edges of the latter, cluster lacing interconnecting the rear edges of said panels and said side sections at a point spaced substantially rearwardly of the forward edge of the latter, tape means disposed over the abdomen and over the diaphragm and adjustably connecting the panels and side sections adjacent the elastic means to supplement the action thereof, belt tensioning means connected to said panels and to said cluster lacing and tape means for simultaneously actuating the same, and elastic webbing of substantial width connected to one of said side sections and adapted to be connected to the other, said webbing covering the pelvic arch of the wearer and completing the coverage and support afforded by said garment.

10. A foundation garment comprising connected rear and side sections partially enclosing the body of the wearer, panels disposed at the ends of but separate from said side sections and extending to meeting relation to one another and adapted to be secured to one another at the free edges thereof, said panels each including a body covering panel substantially overlapping the ends of the first named section on which it is disposed externally of the same whereby gaps are eliminated, elastic means associated with the forward edges of said side sections and said panels to draw the former toward the free edges of the latter, means interconnecting the rear edges of said panels and said side sections at a point spaced substantially rearwardly of the forward edge of the latter, tape means adjustably connecting the panels and side sections adjacent the elastic means to supplement the action thereof, belt tensioning means connected to said panels and to said interconnecting and tape means for simultaneously actuating the same, and elastic webbing of substantial width connected to one of said side sections and adapted to be connected to the other, said webbing covering the pelvic arch of the wearer and completing the coverage and support afforded by said garment.

11. A foundation garment comprising connected rear and side sections partially enclosing the body of the wearer, panels disposed at the ends of but separate from said side sections and extending to meeting relation to one another and adapted to be secured to one another at the free edges thereof, said panels each including a body covering panel substantially overlapping the ends of the first named section on which it is disposed externally of the same whereby gaps are eliminated, elastic means associated with the forward edges of said side sections and said panels to draw the former toward the free edges of the latter, cluster lacing interconnecting the rear edges of said panels and said side sections at a point spaced substantially rearwardly of the forward edge of the latter, tape means disposed over the abdomen and over the diaphragm and adjustably connecting the panels and side sections adjacent the elastic means to supplement the action thereof, and belt tensioning means connected to said panels and to said

cluster lacing and tape means for simultaneously actuating the same, said panels having pockets to receive and conceal the ends of said belt tensioning means.

5 12. A foundation garment comprising connected rear and side sections partially enclosing the body of the wearer, further sections disposed at the ends of said section and extending to meeting relation to one another and adapted to be secured to one another at the free edges thereof, said further panel sections each including a body covering panel substantially overlapping the ends of the first named section on which it is disposed externally of the same, elastic means associated with the forward edges of said side sections and said panel sections to draw the former toward the free edges of the latter, cluster lacing interconnecting the rear edges of said panels and said side sections at a point spaced substantially rearwardly of the forward edge of the latter, tape means adjustably connecting the panels and side sections adjacent the elastic means to supplement the action thereof, and belt tensioning means connected to said panels and to said cluster lacing and tape means for simultaneously actuating the same, said panels having pockets to receive and conceal the ends of said belt tensioning means.

10 13. A foundation garment comprising connected rear and side sections partially enclosing the body of the wearer, further sections disposed at the ends of said section and extending to meeting relation to one another and adapted to be secured to one another at the free edges thereof, said further panel sections each including a body covering panel substantially overlapping the ends of the first named section on which it is disposed externally of the same, elastic means associated with the forward edges of said side sections and said panel sections to draw the former toward the free edges of the latter, cluster lacing interconnecting the rear edges of said panels and said side sections at a point spaced substantially rearwardly of the forward edge of the latter, tape means adjustably connecting the panels and side sections adjacent the elastic means to supplement the action thereof, and belt tensioning means connected to said panels and to said cluster lacing and tape means for simultaneously actuating the same.

15 14. A foundation garment comprising connected rear and side sections partially enclosing the body of the wearer, further sections disposed at the ends of said section and extending to meeting relation to one another and adapted to be secured to one another at the free edges thereof, said further panel sections each including a body covering panel substantially overlapping the ends of the first named section on which it is disposed externally of the same, elastic means associated with the forward edges of said side sections and said panel sections to draw the former toward the free edges of the latter, cluster lacing interconnecting the rear edges of said panels and said side sections at a point spaced substantially rearwardly of the forward edge of the latter, and belt tensioning means connected to said panels and to said cluster lacing for actuating the same.
